UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF DELAWARE.

DEVICE FOR OPERATING CAR COUPLERS.

Original application filed October 8, 1924, Serial No. 742,395. Divided and this application filed March 9, 1925. Serial No. 14,280.

This particular invention relates to what is generally known in the art as a rotating type of uncoupling device for car couplers and comprises an operating rod revolvably 5 mounted on the car with brackets or in any other convenient manner, which rod is usually bent downwardly at the outer end to form a handle, and is bent outwardly at its inner end to form a crank projecting over 10 the coupler lock lifter. The standard vertical plane coupler has a knuckle pivoted to the coupler head and provided with a tail behind which the lock is placed. The lock lifter protrudes through and above the 15 coupler head and is provided with a horizontally positioned eye. This lock lifter eye is $1\frac{1}{16}$ " in diameter and its axis is perpendicular to the longitudinal center of the car. This size and position has been determined 20 by the American Railroad Association and is standard for the majority of couplers now in service.

My invention resides in the connection between the crank of the operating rod and 25 the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component 35 parts becoming disengaged from each other or from either the coupler or the operating rod. It is frequently necessary to uncouple cars when they are coupled together and in contact so that it is impossible to throw the 40 knuckle of either coupler. To meet this condition couplers are designed to assume a "lock set position" wherein the lock lifter can be raised from behind the tail of the knuckle and retained in such a position by 45 means within the head of the coupler independent of the operating rod. This allows the operating rod to fall close to the lock lifter. To accommodate such a movement the connection between the operating rod 50 crank and the coupler must fore-shorten or have a sliding engagement with either the operating rod or the coupler.

Another object is to provide a connection which may be hooked into the eye of the coupler lock lifter with the hooked member 55 connected to the crank of the operating rod by another member which permits it to adapt itself to the various service movements of the coupler but prevents it from becoming disengaged from the lock lifter 60 in service.

In the drawings:

Fig. 1 shows a portion of a railway car with my invention applied thereon.

Figs. 2 and 3 show a form of my device 65 with the nonrotative means independent of the operating rod.

Fig. 4 is a section on line 4—4 of Fig. 2.

Fig. 5 is a section on line 5—5 of Fig. 2.

In a railway car the coupler operating 70 rod 1 is mounted on the end sill 2 by brackets 3 and has a handle 4 at its outer end and a crank arm 5 extending over the coupler. The lock lifter 7 of the coupler 8 has a horizontally disposed eye 9. My invention resides in a connector for the crank arm to the lock lifter. 75

The connector comprises a hook member which is inserted through the eye of the lock lifter and a bar member is then threaded 80 into it so as to close the open portion of the hook.

The bar is prevented from rotating by means independent of the operating rod. The bar 30 is, of course, round where it is 85 threaded into the hook 31 but the shoulder 32 is preferably square (or at least has one flat surface). The hook is provided with a locking lip 33, which is normally as shown in dotted lines in Fig. 4, but is moved to 90 the position shown in full lines after the device is assembled, so as to prevent rotation of the bar whereby the bar 30 and the hook 31 are retained in proper relative position. The type of attachment to the operating rod is immaterial, though preferably 95 slidable. The square shoulder 32 (see Fig. 5) also furnishes a place to apply a wrench or other tool to rotate the bar for engagement or disengagement with the hook or, if 100 desired, the head 34 may be made rectangular for this purpose. The shank of the bar may be round (see Fig. 4) or square or any convenient cross section; in fact, the bar

may be made square throughout its entire length.

This is a division of my co-pending application, Serial No. 742,395, filed October 5, 1924.

I claim:

1. A connector for a railway car coupler lock lifter and its operating rod comprising an open hook member, a bar passing through a portion of said member and having a threaded engagement therewith so as to be rotatable therethrough to open or close said hook and means integral with the hook to prevent the rotation of the bar when desired.

2. In a release rigging for car couplers, the combination of an operating rod, a coupler lock lifter having an eye, an open hook member engaging said eye, a bar passing through a portion of said member and having a threaded engagement therewith so as to be rotatable therethrough to open or close said hook, and means integral with the hook to prevent the rotation of the bar when

desired, said bar rotatably connected to the operating rod.

3. In a device for operating a car coupler lock, the combination of a coupler lock lifter having an eye, a hook member engaging said eye, a bar passing through a portion of said member and having a threaded engagement therewith so as to be rotatable therethrough to open or close said hook, and means integral with the hook to prevent the rotation of the bar when desired.

4. In a device for operating a car coupler lock, the combination of a coupler lock lifter having an eye, a hook member engaging said eye, a bar passing through a portion of said member and having a threaded engagement therewith so as to be rotatable therethrough to open or close said hook and provided with a shoulder to restrict such movement, and means integral with the hook to prevent the rotation of the bar when desired.

ARTHUR E. SMALL.
